WHEELED DEVICE FOR LAUNCHING AND BEACHING SMALL BOATS

George H. Strayer, Erie, Pa.

Application April 17, 1950, Serial No. 156,394

1 Claim. (Cl. 9—1)

1

This invention relates generally to means for making a boat portable on land and it relates more particularly to removable wheeled members for attachment to a small boat for launching and beaching the boat.

All devices of this character, made in accordance with the teachings of the prior art, and with which I am familiar, merely comprise a wheeled axle or buggy separate from the boat. With these prior devices, when beaching a boat it has been necessary to get out of the boat, get a wheeled buggy from storage on the beach, and place it under the rear portion of the boat. It is only with great difficulty that the boat is removed from the water inasmuch as two men must work in water that is generally waist deep with such a device. The boat tends to slip on these prior buggies which adds to the difficulty of beaching a boat. Likewise, when a boat is floated with these prior devices, it is necessary to go into comparatively deep water to remove the carrying buggy from under the boat and place it in safe storage on the beach. It is necessary to beach these prior boat carrying buggies as they are too bulky and heavy to carry in a small boat.

It is, accordingly, an object of my invention to overcome the above and other difficulties in wheeled devices for launching and beaching a boat and it is more particularly an object of my invention to provide a wheeled device for launching and beaching a boat which is simple in construction, economical in cost, economical in manufacture, efficient in operation, and easy to install and remove.

Another object of my invention is to provide wheels for beaching or floating a boat which may be installed and removed from inside the boat.

Another object of my invention is to provide a wheeled device for a small boat whereby the boat may be beached or launched by one man.

Another object of my invention is to provide a wheeled device for beaching and launching a boat which may be removed by a person in the boat and carried in the boat.

Another object of my invention is to provide a wheeled device for launching and beaching a boat which is extremely light and buoyant and which may therefore be carried in the boat as a life preserver.

Another object of my invention is to provide a novel arrangement and construction of detachable wheels for a boat for beaching and launching same.

Another object of my invention is to provide a wheeled device for beaching and launching a boat which permits one man to beach and launch the boat without getting wet, in most instances.

Other objects of my invention will become evi-

2

dent from the following detailed description, taken in conjunction with the accompanying drawings, in which

Fig. 1 is a side elevational view of a boat with one wheel bracket removed;

Fig. 2 is a cross sectional view taken on the line 2—2 of Fig. 1 showing my novel wheeled brackets assembled;

Fig. 3 is an enlarged fragmentary cross sectional view showing the connection attaching one of my wheeled brackets to a boat;

Fig. 4 is an end elevational view of a modified form of wheeled bracket attached to the side of a boat;

Figs. 5 and 6 are side elevational views of the wheeled bracket shown in Fig. 4 assembled on the side of a boat with a brace member for bracing same; and

Fig. 7 is a perspective view of another form of my novel wheeled bracket.

Fig. 8 is a cross sectional view taken on line 8—8 of Fig. 3.

Referring now to the drawings, I show in Figs. 1 to 3 inclusive a conventional flat bottom boat 1 which may be propelled by oars or a motor. Plates 2 are secured to the inner sides 3 of the boat by suitable fastening members 4. The plates 2 have apertures through which extend a tubular member 6 which is welded to the plates 2 at 5. The tubular member 6 has inserts 6a in the ends thereof with a square bore for receiving the square ends 8 of right angled brackets 9. The right angled brackets 9 have outwardly extending shafts 10 upon which are mounted wheels 11 having balloon tires 12 disposed thereon. A metal such as aluminum used for making the brackets 9 and the wheels 11 is extremely light so that the balloon tires 12 make the wheeled brackets 9 buoyant in water. The square ends 8 of the brackets 9 have outwardly extending, opposed, recessed spring catch members 13 for engaging diametrically extending pins 14 in the tubular shaft 6. The spring members 13 have outwardly flared lips 15 so that they pass directly over the pins 14 to a locked position by merely being inserted in the square bored inserts 6a in the ends of the tubular member 6. Conversely, the square portions 8 of the brackets 9 may be withdrawn from the inserts 6a in the ends of the shaft 6 by merely pulling outwardly on the bracket 9 whereby the spring members 13 will expand outwardly and be released from the pins 14 in the shaft 6.

In operation, when the boat approaches a shore or beach and it is desired to beach the boat, it is merely necessary to insert the square stub shaft ends 8 of the brackets 9 in the inserts 6a in the

ends of the shaft 6 with the brackets 9 extending vertically downwardly as shown in Fig. 2. The bow of the boat is then run to the edge of the water so that the operator can get out of the bow of the boat onto the beach without getting wet. The bow of the boat is then tilted upwardly and pulled whereupon the tires 12 engage the bottom, if they have not already done so, and the boat is easily pulled ashore and transported to a storage place. The shaft 6 is placed at the balance point lengthwise of the boat. If an outboard motor is used on the boat, this is taken into consideration in locating the balance point on the boat. A boat may be easily pushed or pulled to any point on the beach with my novel device.

When it is desired to launch the boat, assuming my novel brackets 9 are attached, it is wheeled to the water's edge and then pushed into the water until the bow of the boat reaches the shoreline. In most instances, the shoreline will slope off enough at this point to free the tires 12 on the wheels 11 from the bottom. The operator then gets into the bow of the boat without getting wet and the boat is floated. The boat is then rowed or paddled to deeper water. The operator then reaches over the side and pulls the square ends 8 of the brackets 9 from the inserts 6a in the shaft 6 and the brackets 9 with the wheels 11 are carried in the boat. The buoyant tires 12 may be used as life preservers in case of an emergency.

In Figs. 4 to 6 inclusive, I show a modified form of my invention wherein a bracket 20 is attached by suitable fastening members 21 to the inside of the side 22 of a boat. The bracket 20 has an outwardly extending boss 23 with a vertically extending aperture 24 therethrough for receiving a leg 25 of an inverted U-shaped bracket 26. The leg 25 of the bracket 26 has a transversely extending aperture for registration with a transversely extending aperture 28 in the boss 23 of the bracket 20. A pin 29 is extended through the registered apertures in the leg 25 and boss 23 of the bracket 20, respectively, to lock the leg 25 of the bracket 26 in the aperture 24 in the boss 23 of the bracket 20. A bearing member 30 is mounted on the gunnel 31 of the side 22 of the boat to support the bracket 26. The outer depending leg 32 of the bracket 26 has an outwardly extending shaft 33 for mounting a wheel 34 with a balloon tire 35. The bracket 26 is well supported and will carry all normal sized small boats with motors attached thereto; however, in some instances, I have found it preferable to brace the bracket 26. In this instance, I secure one hooked end of a diagonally extending brace 37 to a bracket 38 attached to the forward part of the gunnel 31 of the side 22 of the boat and the other hooked end is detachably hooked in an aperture 38 in the leg 32 of the bracket 26.

The operation of the wheeled bracket shown in Figs. 4, 5, and 6 is the same as for the wheeled bracket 9 shown in Figs. 1, 2, and 3. With the bracket shown in Figs. 4, 5, and 6, there is no chance for the attaching parts and sockets to be corroded as attachment is on the inside of the boat. It will be apparent that it will only be necessary to register the aperture in the leg 25 of the bracket 26 with the transversely extending aperture 28 in the boss 23 of the bracket 20 and extend a pin 29 therethrough to secure the bracket 26 to the side of the boat. To remove the bracket 26 from the boat after the boat is floated, it is only necessary to pull the pin 29 from the registered apertures. The brace 37 is

merely one with hooked ends so that it may be easily disposed in place and removed. The bearing member 30 may be removable or it may be one which opens for removal of the bracket 26.

In Fig. 7, I show a right angled wheeled bracket 40 with a rectangular shaped upper end 41 secured by brackets 42. The bracket 40 may be used where a boat is decked over either at the bow or on each side amidships thereof.

It will be evident from the foregoing description that I have provided novel wheeled members for attachment to a boat for launching the boat from a beach and for beaching the boat, which may be placed in an operative position and detached from inside the boat while the boat is afloat, which are buoyant and which may be carried in the boat for use as a life preserver, which permit one man to launch and beach a small boat without getting wet, and which are very simple to install and detach.

When my novel wheeled brackets are attached to a boat, the bow thereof may be attached to an automobile or the like for transportation over land. The balloon tires take up much of the impact from travel over rough roads. A wheeled bracket 40 as shown in Fig. 7 may be attached for travel.

Various changes may be made in the specific embodiment of my invention without departing from the spirit thereof or from the scope of the appended claim.

What I claim is:

A wheeled device for transporting a boat comprising an open ended tubular member adapted to be disposed transversely of a boat with the ends thereof coincidental with the outer sides of a boat, brackets having a stub shaft portion for insertion into the ends of said tubular member, wheels carried by said brackets, means for securing said stub shafts of said brackets in the ends of said tubular member against rotation, and snap connecting means for detachably securing the stub shafts of said brackets in the ends of said tubular member, the ends of said tubular member each having a polygonal bore and a pin extending transversely thereof, said stub shaft portions on said brackets being polygonal in shape corresponding to the polygonal shape of said bore and the ends of said stub shafts being split to define snap spring members for connection with the transverse pins in said tubular member.
